Casper L. Redfield

UNITED STATES PATENT OFFICE

CASPER L. REDFIELD, OF CHICAGO, ILLINOIS

HAIR CLIPPER

Application filed February 24, 1930. Serial No. 430,616.

My invention relates to hair clippers, and has for its object improvements in such devices.

In hair clippers in which the motive power is a magnet located inside of a case which serves as a handle for operating the clipper, the magnet is secured firmly to an intermediate point in the length of the case. At one end of the case is fastened a lower 10 blade, commonly called a "stationary blade". On the lower blade is an upper blade commonly called the "movable blade". The upper blade is reciprocated by an armature lever which is secured to the other end of the case 15 and has its central part located adjacent to the pole of the magnet. The magnet may be energized and deenergized by making and breaking a circuit extending to a source of direct current, but is more frequently operated by an alternating current.

When the magnet is energized to move the armature toward the magnet, the same attractive force acts to move the magnet toward the armature. As the magnet is secured to the case, the result is that the case and the lower blade are moved toward the armature when the armature moves toward the magnet, and the case and attached parts are moved from the armature when the armature is retracted. As the case is held in the hand while the clipper is being operated to cut hair, there is a continuous high speed vibration which is not only annoying to the operator, but results in loss of power.

35 The primary object of my invention is to free the magnet and lower blade from direct connection with the case so as to eliminate vibration of the case during operation of the clipper.

40 In the accompanying drawings

Fig. 1 is a plan of the device, with the case in central section;

Fig. 2 is an elevation with the case in section; and

45 Figs. 3, 4 and 5 are transverse sections on lines 3—3, 4—4, and 5—5, respectively.

At the rear end of the device is a support 10 which also serves as a rear head. Cast solid with this head is a lug or projection 11, 50 which is a little off center and projects in-

ward. The side of the projection 11 which is toward the axis of the clipper is in the form of a channel 12, as shown in Fig. 3.

Secured in this channel by a bolt 13 are two metal bars 14 and 15, which are separated from each other by a washer 16 on the bolt. The bar 14 is somewhat heavier than the bar 15, and is held in a fixed position by being clamped against the inclined faces 17 of the channel. The bar 15 is pivoted upon the bolt 13, but has its pivotal movement limited to a very small arc by the parts of the projection 11 which are above and below it. (Fig. 3).

The bars 14 and 15 are of metal which is bendable to take a desired form, but which is flexible and resilient within the range within which they are flexed during operation of the device. That is, they are springs.

These bars lie parallel with each other, but not all parts are the same distance apart. 70 Thus, beginning at a point a short distance beyond the end of the projection 11, the bars are bent outward from each other to enclose a rectangular space, and then back again to substantially their original distance apart. 75

Within the rectangular space between the bars 14 and 15 is a magnet consisting of a coil 18 and a core 19. The core 19 is composed of laminae, two of which have projections 20 which extend thru openings 21 in the bar 14. 80 By bending these projections over on the outer face of the bar 14, the core, and consequently the entire magnet, is firmly secured to the bar 14.

At a point 22, a short distance beyond the point at which they return to practically their original distance apart, the bars 14 and 15 are each given a one-quarter twist so that parts which originally lay vertically side by side, now become extensions 14a and 15a which lie 90 one under the other and are separated by a distance which does not differ materially from the original distance.

The outer end of the extension 14a is bent 95 upward at a desired incline, and a lower blade 23 is secured thereto in a manner common in the art. On the lower blade is an upper blade 24. The extension 15a is given a similar inclination, and is provided with pins 100

25 which project into openings in the blade 24 in a manner also common in the art.

At a place between the magnet 18—19 and the point 22, a spring 27 is secured to the bar 15 and a spring 26 is secured to the bar 14. These springs are connected to the lower edges of bars 14 and 15, and a short distance above the points of connection these springs are bent outward as shown in Fig. 5. Above the bars, 10 these springs are bent inward and overlap with the end of the spring 26 above the end of the spring 27. A screw 28 threaded in the spring 26 and having an end projecting into a hole or recess in the spring 27, serves to apply strain to move the bar 15 downward with respect to the bar 14.

At the front end of the device is a front head 29 in which is an opening 30 thru which project the parts 14a and 15a. Between the 20 heads 10 and 29 is a cylindrical shell or case 31. This shell may be metallic tubing connected to the heads by press fits, but is shown as fiber or other insulating tubing connected to the heads by screws 32.

25 In the bar 14, between the projection 11 and the magnet 18, is a screw 33 which acts upon the armature bar 15 to press it away from the magnet so as to regulate the retractive tension which the magnet has to overcome 30 in attracting the armature.

There are openings in the head 10 for electrical conductors to be connected to the magnet, and other openings in the shell 31 for reaching the screws 28, 33 and 13.

35 By providing suitable make and break devices, the clipper may be operated from a source of direct current. It is more convenient, however, to operate it from a commercial source of alternating current as is 40 common in the art.

When a current flows thru the coil 18, the armature 15 is attracted toward the magnet, and the magnet is attracted toward the armature. This moves the upper blade in the 45 direction that the armature moves, and moves the lower blade in the direction that the magnet moves. These movements are on the point of the screw 33 as a pivot. But because the bar 14 is stiffer than the bar 15, and be- 50 cause the mass carried by the bar 14 is greater than the mass carried by the bar 15, the length of movement of the lower blade 23 is short in comparison to the length of the movement of the upper blade 24. When the current 55 ceases to flow thru the coil 18, the resiliency of the bars 14 and 15 move the lower and upper blades in the reverse directions.

It is to be observed that the apparatus is self-contained, and independent of the case 60 except as for support on the projection. Also, that the case held in the hand is independent of the movements of parts, and consequently free from all vibration.

The screw 33 acts as an adjusting means for 65 regulating the tension of the springs 14 and

15, both of which enter into the operative action of the device. The springs 26 and 27, by bending at parts just above where they are connected to the bars 14 and 15, also act to limit the distances to which the bars 14 and 15 move toward and from each other. 70

While the screw 28 does not regulate the tension of the springs 14 and 15, it does regulate the pressure of the upper blade on the lower one. In this action, the spring is in 75 the overlapping parts of the springs 26 and 27, and adjustment of the lever 15 in a vertical direction comes by reason of the fact that this lever is pivoted on the bolt 13, with only 80 a small washer 16 as frictional surface to resist pivotal movement.

What I claim is:

1. In a device of the class described, a support, two spring bars each secured at one end to said support, a magnet carried by one bar 85 and acting upon the other bar as an armature, and a pair of co-operating blades, one blade being connected to the free end of one bar and the other blade being connected to the free end of the other bar. 90

2. In a device of the class described, a pair of spring actuated bars having a pivotal relation to each other, a magnet acting to move said bars with respect to each other, and cutting blades secured to the free ends of said 95 bars.

3. A support, spring actuated bars each secured at one end to said support, a magnet secured to one bar and acting upon the other bar to attract it, a lower blade secured to the 100 bar which carries the magnet and an upper blade secured to the bar which acts as an armature, and tension means carried by said bars and serving to press the blades together. 105

4. A support, a spring bar secured in a fixed position on said support, a second spring bar pivoted to said support, a magnet carried by the first bar and acting upon the second bar to attract it, a lower blade secured to one bar and an upper blade secured to the other bar, and tension means carried by the 110 bars and acting upon the pivoted bar to move it on its pivot so as to press the blades together. 115

5. A support, a blade moving mechanism carried by said support, a pair of cutting blades carried by said mechanism, and a handle serving as a means for carrying said support and also serving to enclose the blade moving mechanism while being clear of contact therewith. 120

6. A casing, a head closing one end of said casing, an electro-magnetic blade moving mechanism secured to said head and supported within said casing clear of contact therewith, a second head for closing the other end of said casing and providing an opening thru which said mechanism projects clear of the head, and blades secured to the projecting parts of said mechanism. 125 130

7. In a device of the class described, a casing, a pair of cutting blades, and an electro-magnetic blade moving mechanism supported within the casing and serving to move both of said blades clear of contact with said casing.
8. A pair of cutting blades, levers for moving the blades simultaneously in opposite directions for cutting purposes, an electro-magnetic power device for operating said levers, and a spring tension device connected to said levers and serving to regulate the stroke of said levers and also serving to hold the blades yieldingly together.
9. In a device of the class described, a pair of bars supported adjacent to each other, a power device acting to move said bars with respect to each other, cutting blades secured to and moved by said bars, tension means for pressing the blades together, and a casing enclosing said bars but not partaking of the movements thereof.
10. In a device of the class described, a casing, a pair of cutting blades supported by said casing, a power device operating to move the blades with respect to each other and with respect to the casing, and tension means serving to press the blades together while being moved.
11. In a device of the class described, the combination with a pair of blade carriers, and means for moving them with respect to each other, of a spring secured to one carrier and extending over the other, a second spring secured to the second carrier and extending over the first spring, and tension adjusting means interconnecting said springs.
12. In a device of the class described, a casing, a pair of spring bars secured at one end to said casing, one of said bars being materially stiffer than the other bar, a power device mounted upon the stiffer bar and acting to move the other bar, and cutting blades secured to the free ends of said bars.

CASPER L. REDFIELD.
